US00D488453S

(12) **United States Design Patent** (10) Patent No.: **US D488,453 S**
(45) Date of Patent: **** Apr. 13, 2004**

(54) **MOBILE COMMUNICATION DEVICE**

(75) Inventors: **Jackson Chang**, Taipei (TW); **Chin-Fa Lee**, Taipei (TW); **Chi-Yu Ho**, Taipei (TW)

(73) Assignee: **Inventec Appliances Corporation (TW)**

(**) Term: **14 Years**

(21) Appl. No.: **29/182,757**

(22) Filed: **Jun. 2, 2003**

(51) LOC (7) Cl. **14-03**

(52) U.S. Cl. **D14/138**

(58) Field of Search **D14/137, 138, D14/218, 147-148, 247-248, 144, 341-347; 379/433.01-433.13, 419, 434, 428.01-428.04, 420.01-420.04, 440; 455/550.1-90.3; D21/517**

(57) **CLAIM**

The ornamental design for a mobile communication device, as shown and described.

DESCRIPTION

FIG. 1 is a perspective view thereof;
FIG. 2 is a bottom plan view thereof;
FIG. 3 is a top plan view thereof;
FIG. 4 is a left side view thereof;
FIG. 5 is a right side view thereof;
FIG. 6 is a front side view thereof;
FIG. 7 is a rear side view thereof;
FIG. 8 is a perspective view inside the device thereof;
FIG. 9 is a perspective view showing a used state of the mobile communication device by rotating its button plate about an axis to turn into a standing mode;
FIG. 10 is a perspective view showing a used state of the mobile communication device by rotating its button plate about another axis to turn into another standing mode from the mode shown in FIG. 9;
FIG. 11 is a perspective view showing a used state of the mobile communication device by rotating its button plate to still another standing mode from the mode shown in FIG. 10; and,
FIG. 12 is a perspective view showing a used state of the mobile communication device by rotating its button plate to an operable mode from the mode shown in FIG. 11.
